OF CHICAGO, ILLINOIS.

HOISTING AND DUMPING APPARATUS.

Application filed August 5, 1921. Serial No. 489,940.

To all whom it may concern:

Be it known that we, GEORGE N. SIMPSON and ARTHUR M. SIMPSON, citizens of the United States, residing at Pittsburgh, Allegheny County, Pennsylvania, and 1220 East 75th Street, Chicago, in the county of Cook and State of Illinois, have invented a new and useful Improvement in Hoisting and Dumping Apparatus, of which the following 10 is a specification.

This invention relates to improvements in hoisting and dumping apparatus designed to elevate a car loaded with coal, ore or other material and overturn the car at the 15 top of its elevation for the purpose of dumping its contents. In general, the apparatus comprises a hoisting cage adapted to receive the loaded car at the foot of a shaft or other dumping place and raise it 20 to the top; where the car supporting parts in the cage are engaged in such manner as to rotate them and overturn the car in order to empty it of its load.

In that form of the device embodying the 25 features of the invention shown in the accompanying drawings, Figure 1 is a view in side elevation of the improved hoisting cage, Fig. 2 is a view similar to Fig. 1 showing the cage in end elevation, with a car in place in the cage, Fig. 3 is a view taken as indicated by the line 3 of Fig. 2, showing the cage, however, in a higher position with the car inside overturned, Fig. 4 is a top plan view of the interior of the cage, Fig. 5 is a view taken as indicated by the line 5 of Fig. 4, Fig. 6 is a view in end elevation of the car supporting cradle within the cage, Fig. 7 is a view taken as indicated by the line 7 of Fig. 1, Fig. 8 is a view 30 taken as indicated by the line 8 of Fig. 4 and Fig. 9 is a vertical sectional view of one of the guiding shoes on the cage.

As shown in the drawings, the device 40 comprises a hoisting cage indicated in general by A. The cage A is formed of the two large side plates 10; 10 which are substantially rectangular in shape at the top and beveled at the bottom edges. Each of the plates 10 has riveted on its outer side 45 a vertical channel member 11. The plates 10 are connected by the horizontal channel members 13 on one side and by the channel members 14 on the other. Each of the plates 10 is further strengthened and stiff-

fened by the diagonally arranged channel irons 15 riveted to its outer side and by the horizontal member 16 attached in the same manner. Reinforcing channel irons 17 are attached to the plates 10 at the top and next to the upper ends of the members 11. The members 17 have their upper ends joined by the channel irons 12. The edges of the plates 10 are suitably stiffened, strengthened and braced by the angle irons 18 which are riveted to such edges. Mounted on each side of the cage are two guiding shoes indicated in general by B adapted to engage with suitable guides or rails 19 at the sides of the shaft in order to hold the cage true in its course during ascent 50 and descent in the shaft. One of the shoes B will be described more in detail hereinafter.

Within the cage A is journalled a car 55 supporting cradle indicated in general by C. Mounted on the cradle C are track rails 21 which extend substantially the length of the cradle and are somewhat inclined from end to end so that a car 22 which is placed on them will rest against stops 23 secured to the rails near their lower ends to keep the car from rolling out of the cradle. The stops 23 are hinged to the rails so that they may be displaced laterally to permit the empty car to roll forward out of the cage on the return of the latter to the bottom of the shaft. The stops are controlled through a toggle arrangement of levers so designed that the stops are automatically released when the cage reaches 60 the bottom of the shaft. The particular design of this part of the mechanism will be explained more in detail hereinafter.

The cradle C is provided with trunnions 65 which are journalled in bearings 26 mounted on the inner sides of the plates 10. Each of the trunnions 25 is bored out and adapted to receive a cylindrical part 27 on the outer end of which is mounted a turning arm 28. The part 27 is held in place 70 in the trunnion 25 by a bolt 29, and rotation with respect to the trunnion is prevented by a key 30. The cylindrical part 27 has its outer end outside of the trunnion 25 enlarged to the same diameter as the trunnion itself, thus forming the shoulder 31. The plate 10 is provided with a hole in alignment with the trunnion 25 to accom-

modate the enlarged outer end of the cylindrical part 27, and the arm 28 lies outside of the plate 10. Each of the arms 28 has mounted on its end an elongated guiding shoe 33 substantially rectangular in shape and rounded on its ends. It will be seen that by this construction, swinging of the arms 28 will serve to rock the cradle C, so that a car in position upon the cradle 10 can be overturned and dumped. It is obvious, however, that some means must be provided for holding the car on the rails 21 during the overturning of the cradle. In order to accomplish this the cradle is provided on its sides with two angle irons 35 arranged with their horizontal webs projecting inwardly and lying above the rails 21 and of just sufficient height to permit the wheels 36 of the car 22 to roll thereunder. It will be seen that the angle irons 35 will serve, therefore, to hold the wheels 36 on the rails 21 and thus prevent the car 22 from leaving the rails during the overturning operation.

25 Overturning of the cradle C in order to dump the car 22 is effected in the following manner. Arranged at the sides of the shaft at the top, where the dumping of the car is to take place, are two Y-shaped guides or 30 grooves 40 in which the shoes 33 are adapted to slide. When the cradle C is in its normal upright position, the arms 28 are substantially vertical as shown in Fig. 1. In Fig. 1 the cage A is shown near the top 35 of the shaft with the shoe 33 just entering the guide 40. From this point on, upward movement of the cage A will cause the shoe 33 to slide in the guide 40 thus moving the arm 28 and rocking the cradle 40 C. The progressive positions assumed by the shoe 33 and arm 28 caused by the sliding of the shoe 33 in the guide 40 as the cage A ascends are indicated in Fig. 1, by 33^a, 33^b, and 33^c. In Fig. 3 the cage is shown 45 at the top of its travel with the cradle C almost completely overturned and the car 22 dumped. The cage A is hoisted in the shaft in any desired manner, as, for example, by suitable cables 12^a attached to the members 12 and operated by suitable hoisting machinery. The particular means for hoisting the cage A form no part of the present invention and consequently are not 50 shown herein.

55 At the bottom of the cage is arranged a slanting chute 45 formed of a flat sheet of metal joining the two lower slanting edges of the plates 10. The chute 45 is arranged to catch the contents of the car when the latter is overturned. Hinged at the lower edge of this chute 45 is a swinging apron 46, designed to drop downward into a position as indicated in Fig. 3 when the cage 60 is at the top of its travel and the cradle with

the car thereon is in dumping position. 65 When the apron is in this position it forms an extension of the chute 45, and slightly overlaps the same on the underside of the chute 45; in order to convey material which may slide from the chute 45, to one side of the shaft opening to deposit the same in any suitable bin or other receptacle. When the cage A is at the bottom of the shaft, the apron 46 is swung up into a vertical position as shown in Fig. 1. The parts are so 70 arranged that the apron 46 stays in this vertical or closed position for some time after the cradle C has commenced to rotate and dump the contents of the car. During the first part of the dumping, therefore, the contents from the car are retained on the chute 45 against the vertical closed apron 46. After the car has overturned somewhat more than 90°, the apron 46 commences to 75 lower. When the cage has reached the top 80 of its upward movement the apron 46 is completely lowered as shown in Fig. 3 and the car 22 has reached the limit of its overturning motion. One of the purposes of holding the material dumped against the 85 apron 46 is to prevent a long fall of material from the car. With the apparatus as shown, the material spills rather than falls from the car upon the chute 45 where it is held by the apron 46 until practically the entire 90 contents of the car have been deposited upon the chute 45; when the apron 46 opens and allows all the material to slide down from the chute 45 over the apron 46 into any suitable receptacle provided. By this arrangement also the material is prevented from being emptied during a long travel of the cage. It will be noted that the upward movement of the cage overturns the cradle and car thereon. This overturning cannot 95 be done too rapidly owing to the fact that the cradle and car have considerable weight and must be moved relatively slowly. On this account, therefore, the complete overturning of the car requires considerable upward movement of the cage A. If it were not for the arrangement of the chute 45 and apron 46, material would commence to 100 spill out of the car 22 as soon as it had slightly overturned and continue to thus spill out during all the remaining overturning of the car until the car was completely emptied. Since, during this time, the cage 105 would make considerable progress in its upward movement, it would be difficult to collect or gather the material thus dumped from the car during all this movement of the cage. In order to avoid this difficulty the chute 45 and apron 46 are arranged to 110 collect the material therein until the car is practically completely dumped. The apron 46, being relatively light in weight, can 115 then be quickly opened by a short upward 120 movement. The car 22 is then dumped 125

travel of the cage A, thus allowing all the material gathered on the chute 45 to flow out into a receptacle provided therefor. The method of operating the apron 46 is as follows. It has near its lower edge two rollers 47 adapted to engage with and roll against vertical guides 48 arranged at the side of the shaft. The guides 48 extend from near the top of the shaft to near the bottom and serve to hold the apron 46 in its raised and closed position as shown in Fig. 1 during the upward travel of the cage A until it gets almost to the top. Near the top of the shaft, the guides 48 are bent as indicated by 49 away from the shaft to form horizontal guides 50. Above the guides 48 are additional guides 51 the lower ends of which are bent inwardly somewhat as indicated by 52 to overlap the guides 48. There is sufficient distance between the ends 52 of the guides 51 and the curved parts 49 of the guides 48 to accommodate the rollers 47. It will be seen that, by this construction, when during upward movement of the cage A the rollers 47 engage the ends 52 of the guides 51 the apron 46 will commence to be lowered; and that thereafter upward movement of the cage will cause the rollers 47 to roll out on the horizontal guides 50 thus allowing the apron 46 to reach its lowest or full open position. Continued upward movement of the cage A will lift the rollers 47 somewhat from the guides 50 and cause them to roll on the guides 52; but during this movement the apron 46 will remain down or open as shown in Fig. 3. The bend 49 in the guides 48 is so located, as explained before, to cause the apron 46 to commence to lower or open after the cradle has been partly overturned and the contents of the car 22 practically all deposited on the chute 45 back of the apron 46. From the time the apron 46 commences to lower, continued upward movement of the cage A completes the overturning of the car 22 and allows the apron 46 to reach its lowest or completely open position as shown in Fig. 3.

The apron 46 is provided with vertical side plates 54 adapted to keep material passing over the apron 46 from falling off of the sides thereof. The plates 54 are adapted to overlap the bottom corners of the plates 10 when the apron 46 is in its raised or closed position. The apron 46 is hinged at the lower edge of the chute 45 in the following manner, as best illustrated in Fig. 7. The bottom corners of the plates 10 are reinforced by plates 56. Round holes are cut through the corners of the plates 10 and reinforcing plates 56, and through these holes is inserted a pipe 57 of sufficient length so that its ends will project somewhat beyond the outer sides of the reinforcing plates 56. The vertical side plates 54 on the apron

46 are provided with corresponding holes through which the pipe 57 is inserted. The holes in the plates 54 are reinforced by circular castings 58 bolted to the plates 54. The parts are assembled by placing the apron 70 in position so that the holes in the plates 54 will register with the holes in the plates 10 and then inserting the pipe 57. The pipe 57 has sufficient length so that its ends will project somewhat beyond the castings 58, 75 and is prevented from endwise displacement by pins 59 extending through the ends of the pipe 57.

We will now describe more in detail the construction and operation of the stops 23 arranged on the rails 21 which prevent the car 22 from rolling forward on the rails during the dumping operation. Especial reference is directed to Figs. 4, 5 and 6. It will be seen that the stops or horns 23 are mounted on horizontal shafts, the ends of which are swiveled in boxes 60 fastened to the outsides of the rails 21. It will be seen that by this construction the horns 23 may be moved from a closed position as shown in Fig. 2 with their ends lying above the rails 21, to an open position as shown in Fig. 4 with their ends lying to the outside of the rails 21. Their movement is so limited that when they are in the closed position above the rails, they will lie in the path of the car wheels 36; and that when they are in their open position as shown in Fig. 4, they will be outside the path of the car wheels and allow the same to pass. The horns or stops 23 are adapted to be moved from their open to their closed position and vice versa by a toggle arrangement of levers connected to a horizontal rotatable shaft 62 arranged on the cradle C in the center slightly below the rails 21. Each of the horns 23 has a downwardly extending arm 63. The end of the shaft 62 has mounted thereon two oppositely arranged radial arms 64. Each of the arms 64 is connected to a corresponding arm 63 by a connecting rod 65. It will be seen that, through the arms 64, connecting rods 65 and arms 63, rotation of the shaft 62 will cause movement of the stops or horns 23. The other end of the shaft 62 has mounted thereon a fan-shaped lever 66. At about the center, the shaft 62 is also provided with a downwardly extending arm 67 the end of which is connected by a spiral spring 68 to a stationary part of the cradle C. The parts are so arranged that the spring 68 will tend normally to rotate the rod 62 to cause the stops 23 to lie in their closed position above the rails 21. When in this position the fan-shaped lever 66 is in the position as indicated by the broken lines in Fig. 2. At the bottom of the shaft is arranged a stationary stop 70 adapted to engage the end of the lever 66 when the cage A is almost at the end of its downward 130

travel; so that the last part of the downward travel of the cage will cause the end of the lever 66 to be raised (with respect to the cradle C) and the shaft 62 rotated about 5°. The parts are so arranged that this amount of rotation of the shaft 62 will operate to move the stops 23 to their open position out of the path of car wheels on the rails 21. It will be seen that by this construction, as the cage A reaches the bottom 10 of the shaft, engagement of the fan lever 66 with the stop 70 will operate automatically to open the stop 23 and allow the car on the cradle C to roll on the slanting rails 21, and 15 pass out of the cage. If the stops 23 were allowed to remain in this open position after the emptied car had passed out, there would be nothing to stop the new loaded car from passing right through the cage and out 20 again. The following means, therefore, are provided for again restoring the stops 23 to their closed position in order to stop the new loaded car as it enters the cage. The shaft 62 has a certain amount of endwise 25 sliding movement. This movement is sufficient to allow the lever 66 to become disengaged from the stop 70. When thus disengaged it is obvious that the spring 68 will operate to again close the stops. Near the 30 high ends of the rails 21 are arranged two triggers 73 adapted to be engaged by the flanges of the car wheels entering the cage. The triggers 73 are mounted on a transversely arranged shaft 74 rotatably mounted 35 on the cradle C below the rails 21 in such a manner that they will be depressed as the wheels 36 of the car 22 pass over them. They will not, however, block the passage of such wheels. The downward movement of the 40 triggers 73 caused by the passage over them of wheels on a car operate to slide the shaft 62 endwise to release the lever 66 from the stop 70 so that the horns or stops 23 will be closed. The distance between the stops 23 45 and triggers 73 is so short, that the empty car has passed from the cage beyond the stops 23 before the wheels of a new incoming car engage the triggers 73 to cause the stops 23 again to be set. By this construction 50 it will be seen that as the cage reaches the bottom of its travel, the stops 23 will automatically be opened, the empty car will run out; and a new loaded car entering the cage will depress the triggers 73 to cause the 55 stops 23 again to be set or closed and thus hold the new loaded car in the cage for the subsequent elevating of the cage and dumping operation. The endwise movement of the shaft 62, referred to above, caused by 60 the movement of the triggers 73, is accomplished in the following manner. The shaft 62 is provided with a collar 76 adapted to be engaged by two dogs 77, one on each side of the shaft 62. The dogs 77 are keyed on 65 to the shaft 74 so that rotation of this shaft

causes movement of the dogs 77 against the collar 76 to move the shaft 62 endwise. After the passage of the car wheels over the triggers 73 they are again restored to their normal upright position by a spiral spring 78 having one end attached to the lower end of an arm 79 mounted on the shaft 74 and its other end attached to any suitable stationary part on the cradle C. A spiral spring 80 on the shaft 62 with its end against the 75 collar 81 operates to move the shaft 62 endwise to its normal position after the stops 23 are again brought to their closed position and after the triggers 73 are again raised to their normal upright position by the spring 80 78 after the passage of the car wheels.

We will now describe more in detail the construction of one of the shoes B. At each side of the channel member 11 is a short angle iron 90 mounted on the plate 10. Since 85 the two sides of the shoe B are similar I will describe in detail but one. The web 91 of the angle iron 90 lies at right angles to the plate 10 and is somewhat wider than the edge of the channel member 11. Mounted 90 on the inner side of the web 91 is a flat strap of metal 92 with its ends bent outwardly as indicated by 93. The metal strap 92 is fastened to the web 91 by bolts 94 and spaced therefrom by washers 95 on 95 such bolts. It will be seen that by this construction, the straps 92 may be located as close to each other as desired by changing the number or thickness of the washers on the bolts 94. This construction adapts 100 the shoes to be altered easily to fit different sizes of guides 19 at the sides of the mine shaft. Mounted on the channel member 11 is another plate 96 similar to the plates 92 and spaced from the channel member 11 by 105 washers similar to the washers on the bolts 97 which hold the strap 96 in place. The mounting of this strap 96 on the channel member 11 is similar to the mounting of the strap 92 on the web 91. By the use of 110 washers of different thickness behind strap 96 it also may be placed close to or away from the shaft in order to fit the guides 19.

It is to be noted that the device shown 115 permits the hoisting and dumping of solid body cars, that is, cars having no gates. The device, however, will also operate with gate cars if desired. Among the other advantages of the device, it may be mentioned that this device retains the complete weight 120 of the cage and the car on the hoisting rope during the entire dumping operation. This is an advantage since it makes the counter balancing more easy.

While we have shown and described but 125 a single embodiment of our invention, it is to be understood that it is capable of many modifications. Changes, therefore, in the construction and arrangement may be made without departing from the spirit and 130

scope of our invention as disclosed in the appended claims, in which it is our intention to claim all the novelty inherent in our invention as broadly as is possible in view of the prior art.

We claim:

1. In a car hoisting and dumping apparatus, a cage adapted to receive a loaded car, a rotatable car supporting cradle within such cage, an arm attached to the cradle, a shoe on the end of the arm, means for hoisting the cage, and means acting through the movement of the cage to turn the arm to rotate the cradle and overturn the car, 15 said means including a Y-shaped guide adapted to engage the shoe on the end of the arm.

2. In a car hoisting and dumping apparatus, a cage adapted to receive a loaded car, 20 a rotatable car supporting cradle within such cage, an arm attached to the cradle, a shoe on the end of the arm, means for hoisting the cage independently of the cradle, and means acting through the movement of the cage and independently of the hoisting means to move the arm to rotate the cradle and overturn the car, said means including a Y-shaped guide adapted to engage the shoe on the end of the arm.

3. In a car hoisting and dumping apparatus, a cage adapted to receive a loaded car, a rotatable car supporting cradle within such cage, an arm attached to the cradle, means for hoisting the cage, a Y-shaped stationary part located at the top of the path of the movement of the cage, and a part on the arm attached to the cradle adapted to engage with such stationary part to move the arm to rotate the cradle and overturn 40 the car.

4. In a car hoisting and dumping apparatus, a cage adapted to receive a loaded car, a rotatable car supporting cradle within such cage, an arm attached to the cradle, 45 a Y-shaped guide located at the top of the path of movement of such cage, and a part on the arm attached to the cradle adapted to engage with such guide to move the arm to rotate the cradle and overturn the car.

5. In a car hoisting and dumping apparatus, a cage adapted to receive a loaded car, a rotatable car supporting cradle within such cage, an arm attached to the cradle, 55 a Y-shaped guide located at the top of the path of movement of such cage, and a shoe on the end of the arm adapted to engage with the guide to move the arm to rotate the cradle and overturn the car.

6. In a car hoisting and dumping apparatus, a cage adapted to receive a loaded car, 60 a rotatable car supporting cradle within such cage, an arm attached to the cradle, means for hoisting the cage, means acting through the movement of the cage to move the arm to rotate the cradle and overturn the

car, a chute carried by the cage below the cradle, and a movable apron connected to the chute.

7. In a car hoisting and dumping apparatus, a cage adapted to receive a loaded car, 70 a rotatable car supporting cradle within such cage, an arm attached to the cradle, means for hoisting the cage, means acting through the movement of the cage to move the arm to rotate the cradle and overturn the car, a chute carried by the cage below the cradle, a movable apron connected to the chute, and means acting through the movement of the cage to move the apron.

8. In a car hoisting and dumping apparatus, a cage adapted to receive a loaded car, 80 a rotatable car supporting cradle within such cage, an arm attached to the cradle, means for hoisting the cage, means acting through the movement of the cage to move 85 the arm to rotate the cradle and overturn the car, a chute carried by the cage below the cradle, an apron hinged to the lower edge of the chute, and means acting through upward movement of the cage to lower or open 90 the apron.

9. In a car hoisting and dumping apparatus, a cage adapted to receive a loaded car, 95 a rotatable car supporting cradle within such cage, an arm attached to the cradle, means for hoisting the cage, means acting through the movement of the cage to move the arm to rotate the cradle and overturn the car, a chute carried by the cage below the cradle, an apron hinged to the lower edge 100 of the chute, and means acting through downward movement of the cage to raise or close the apron.

10. In a car hoisting and dumping apparatus, a cage adapted to receive a loaded car, 105 a rotatable car supporting cradle within such cage, an arm attached to the cradle, means for hoisting the cage, means acting through the movement of the cage to move the arm to rotate the cradle and overturn the car, a chute carried by the cage below the cradle, an apron hinged to the lower edge of the chute, and means acting through upward movement of the cage to lower or open 110 the apron and means acting through downward movement of the cage to raise or close the apron.

11. In a car hoisting and dumping apparatus, a cage adapted to receive a loaded car, 120 means acting through movement of the cage to overturn the car, a chute carried by the cage below the car, an apron hinged to the lower edge of the chute, such apron adapted to be moved by movement of the cage.

12. In a car hoisting and dumping apparatus, a cage adapted to receive a loaded car, 130 means acting through movement of the cage to overturn the car, a chute carried by the cage below the car, an apron hinged to the

lower edge of the chute, such apron adapted to be raised to its closed position by downward movement of the cage.

13. In a car hoisting and dumping apparatus, a cage adapted to receive a loaded car, means acting through movement of the cage to overturn the car, a chute carried by the cage below the car, an apron hinged to the lower edge of the chute, such apron adapted to be lowered to its open position by upward movement of the cage.

14. In a car hoisting and dumping apparatus, a cage adapted to receive a loaded car, means acting through movement of the cage to overturn the car, a chute carried by the cage below the car, an apron hinged to the lower edge of the chute, such apron adapted to be raised to its closed position by downward movement of the cage and lowered to its open position by upward movement of the cage.

15. In a car hoisting and dumping apparatus, a cage adapted to receive a loaded car, means for hoisting the cage, means acting through movement of the cage to overturn the car, a chute carried by the cage below the car, and an apron with vertical side plates hinged to the lower edge of the chute, the hinged joint being effected by a pipe

mounted on the cage with its ends extending through the vertical side plates on the apron.

16. In a car hoisting and dumping apparatus, a cage adapted to receive a loaded car, a rotatable car supporting cradle within such cage, an arm attached to the cradle, means for hoisting the cage, and means acting through the movement of the cage to turn the arm to rotate the cradle and overturn the car, said means comprising an elongated shoe on the end of the arm adapted to engage with a guide at the side of the shaft.

17. In a car hoisting and dumping apparatus, a cage adapted to receive a loaded car, a rotatable car supporting cradle within such cage, an arm attached to the cradle, means for hoisting the cage, and means acting through the movement of the cage to turn the arm to rotate the cradle and overturn the car, said means comprising an elongated shoe on the end of the arm adapted to engage with a Y-shaped guide at the side of the shaft.

In witness whereof we have hereunto set our hands and seals this 27 day of June, 1921.

GEORGE N. SIMPSON. [L. S.]
ARTHUR M. SIMPSON. [L. S.]
